US00D654913S

(12) **United States Design Patent**
Townsend

(10) **Patent No.:** US D654,913 S
(45) **Date of Patent:** ** Feb. 28, 2012

(54) **USER INTERFACE FOR COMMUNICATION DEVICES**

(76) Inventor: **Michael L. Townsend**, Legigh Acres, FL (US)

(**) Term: **14 Years**

(21) Appl. No.: **29/372,685**

(22) Filed: **Dec. 23, 2010**

(51) **LOC (9) Cl.** 14-03

(52) **U.S. Cl.** D14/247

(58) **Field of Classification Search** ..... D14/138 R, D14/138 AD, 138 AC, 138 C, 138 G, 191, D14/203.1-203.8, 496, 138 AA, 138 AB, D14/137, 147, 218, 341-347, 247-248; D10/65, D10/78, 104; D13/168; D18/7; 455/566, 455/575.1, 575.3, 575.4

See application file for complete search history.

CLAIM

The ornamental design for a user interface for communication devices, as shown and described.

DESCRIPTION

The sole drawing FIGURE is a front view of a user interface for communication devices showing my new design.

The evenly spaced broken lines and the dot-dash broken lines are directed to environment and are for illustrative purposes only; such broken lines form no part of the claimed design.
